UNITED STATES PATENT OFFICE.

THOMAS McG. AIKEN, OF PITTSBURGH, PENNSYLVANIA.

FRUIT AND VEGETABLE SLICER.

1,156,652.

Specification of Letters Patent.

Patented Oct. 12, 1915.

Application filed January 27, 1915. Serial No. 4,648.

To all whom it may concern:

Be it known that I, THOMAS McG. AIKEN, a citizen of the United States, and a resident of Pittsburgh, in the county of Allegheny, and State of Pennsylvania, have invented 5 certain new and useful Improvements in Fruit and Vegetable Slicers, of which the following is a specification.

The object of this invention is to provide 10 a simple and efficient tool for slicing vegetables and fruits, the tool being of such construction that when held in flat engagement with the surface to be cut the resulting slice is necessarily of uniform thickness.

15 A further object is to provide for adjusting the cutter for slices of different thickness without impairing the uniformity of the slice whether it be relatively thick or thin.

The invention is embodied in a tool-like 20 body portion or head having a bottom guiding surface which is adapted to bear on the article to be cut together with a blade-like cutter adjustable relatively to said surface but always maintained parallel therewith, so 25 that so long as the guiding surface is maintained in proper engagement with the article a slice of uniform thickness will be produced. And it is in this particular that the invention distinguishes from those hand-manipulated 30 slicing tools heretofore proposed wherein uniformity in the thickness of the slice depends entirely upon the skill of the operator, the tool being provided with no automatic gaging means for compelling uniformity.

In the accompanying drawings, Figure 1 is a view in top plan of a tool embodying 35 the invention, and Fig. 2 is a longitudinal section on line 2-2 of Fig. 1. Fig. 3 is a bottom plan. Fig. 4 is a cross-section of the tool taken on line 4-4 of Fig. 2. Fig. 5 is a view in top plan of a tool of modified form, and Fig. 6 is a longitudinal section on line 6-6 of Fig. 5.

45 Referring to the drawings, the tool body is of open-top shell-like form, being preferably shaped or pressed from sheet-metal and consists of a transversely elongated head-like portion A having its bottom formed 50 with the guiding or gaging surface B, the head at each end of said surface provided with the upstanding end portions or wings C. The edges of these wings are inclined upwardly and forwardly from the marginal portion b of guiding surface B, and are 55 formed with the straight parallel bead-like

grooves D which adjustably confine the cutter support, as will be presently described.

At the opposite side of the gage surface B from marginal portion b the metal of the head or body is inclined upwardly and forwardly and curled to form the hollow handle extension E. In the adaptation shown in Figs. 1, 2 and 3, handle portion E comprises a socket for the removable curved paring 60 and coring blade F, the handle G of which provides a convenient handle for the slicing tool. The inset lips or flanges H in handle portion E overhang the edges of blade F, the latter wedging therebeneath and firmly 65 held in the socket with the blade point F' confined in the lower extremity of the socket-like handle formation of the body. In the adaptation shown in Figs. 5 and 6 the contracted and curled handle portion J is extended to form an integral handle of full 70 length, the extremity of which may be shaped to form the peeler and corer K. In this formation the curled sides of the handle are preferably flattened, as indicated at J', 75 to provide for conveniently and securely gripping the same.

The guiding or gaging surface B is preferably flat, and the blade-like cutter L is also flat, with its cutting edge l disposed 80 toward marginal portion b of surface B. Blade L is maintained in a plane constantly parallel with the plane of surface B, the distance separating said planes determining the thickness of the slice. For thus adjustably supporting the cutter, the extremities thereof are secured to the upwardly and forwardly inclined parallel arms M which are 85 slidable in guide grooves D of the upstanding head-ends C. Arms M preferably are 90 extensions of the transverse bar N, all being bent up from a piece of wire of suitable gage with the arm terminals secured in sockets L' at the ends of blade L and with the extremities of said terminals turned upwardly slightly at M' to prevent the terminals from pulling out the socket. With arms N slidable in parallel guides D the 95 parallelism of the blade and surface B is maintained whether the blade be set for producing a relatively thick or thin slice.

In the adaptation shown in Figs. 1 to 4, a clamping device O is hinged to turn on bar N of the blade, and when the clamp is turned to holding position its hook-like extremities 100 P are adapted to flex over the heads which form grooves D and thereby lock the cutter

in the adjustment in which it is set. The clamp may be conveniently released by finger pressure on the tail-piece Q, and restored to clamping position by pressure on 5 the loop-like portion Q', parts Q and Q' being arranged at opposite sides of the hinge center of the clamp.

The use of a blade clamp is optional. When employed the guideway for the cutter 10 carrier may be disposed at a less acute angle to surface B, the clamp preventing the blade from being withdrawn and lowered by reason of its engagement with the article being cut. If no clamp is employed, as in 15 the construction shown in Figs. 5 and 6, the cutter support must be adjustable in a plane more nearly at right angles to surface B, the angle being necessarily sufficient to prevent the pull on the cutter from dragging 20 the support downwardly in its guideways. In this last described construction the tool is necessarily thicker, wider or less flat in its dimension extending from top to bottom than in the construction employing a clamp. 25 In operation, after adjusting the cutter for the desired thickness of slice the tool is grasped by its handle and drawn over the potato, apple or other article with surface B held in flat engagement therewith. The 30 operation is thus accurately gaged, the parallelism of the blade and surface B compelling a slice of uniform thickness from end to end. This effect is further facilitated by beveling the upper side of cutting edge l, 35 as shown.

I claim:

1. A household tool comprising a handle, a guiding device and a blade-like cutter carried by the handle, the guiding device having 40 a straight bearing surface extending in the direction of movement of the tool and the blade-like cutter having its width dimension extending in the same direction with its cutting edge disposed transversely to said 45 direction of movement, the cutter and guiding device being spaced apart in the direction of said movement and with the straight guiding surface and transverse dimension of the cutter lying in parallel planes, and 50 means for varying the distance between said planes.

2. A household tool comprising a body having its under side straight in the direction of movement of the body to form a 55 guiding surface, a handle projecting from the body, a cutter spaced from the body in the direction of movement of the tool with the cutter straight in said direction and lying in a plane parallel with the guiding surface of the body, and a cutter support secured to the body and adjustable thereon in a straight line oblique to the planes of 60 said guiding surface and cutter for varying the distance between the planes of said parts 65 without disturbing their parallelism.

3. A household tool comprising a body having its under side formed with a flat guiding surface and with a handle portion inclined upwardly and rearwardly from said surface, a flat cutter at one side of the guiding surface and in a plane beneath and parallel therewith, and a cutter support carried by the body and movable thereon in a right line for maintaining the flat guiding surface and flat cutter parallel in all positions of adjustment. 70 75

4. A household tool comprising a body having its under side formed with a flat guiding surface and with a handle elevated above said surface, a flat cutter parallel 80 with the flat guiding surface, cutter-supporting means movable on the body for maintaining the flat cutter parallel with the flat guiding surface in all positions of adjustment, the guiding surface and the cutter 85 being spaced apart in the direction in which the tool is moved by the handle.

5. A household tool comprising a body having its under side formed with a flat guiding surface, a handle projecting from 90 the body at one side of the guiding surface and a flat cutter at the opposite side of and in a plane parallel with the flat guiding surface, a cutter support movable on the body for varying the distance between the parallel 95 planes of the guiding surface and cutter, the support being movable in a direction to maintain such parallelism in all positions of the cutter. 100

6. A household tool comprising a body having a transversely disposed head-like portion formed on its under side with a flat guiding surface and with an upwardly disposed handle portion at one side of said surface, a flat blade-like cutter lying in a plane 105 parallel with the guiding surface and located at the opposite side of the latter from the handle, a cutter support adjustable on the body for maintaining the cutter parallel with the guiding face in all positions of adjustment. 110

7. A household tool comprising an upwardly open shell-like body having a transversely widened head-like portion provided with upstanding ends, the under side of the head-like portion between said ends being flat to form a guiding surface, the metal of the body disposed upwardly from said flat surface and contracted to provide a handle portion, a flat blade-like cutter disposed in a plane lower than and parallel with the guiding surface and located at the opposite side of said surface from said handle portion, and a cutter carrier, the upstanding ends of the head-like portion shaped to adjustably retain the carrier whereby the setting of the flat cutter may be varied relatively to the flat guiding surface and maintained always parallel therewith. 115 120 125

8. A household tool comprising an up- 130

wardly open shell-like body, the body being widened transversely to form a head-like portion, the under side of the latter formed with a flat guiding face and said head portion having upstanding ends formed with inclined parallel edges and each edge formed with a straight guideway, the body at one side of its flat guiding face being upwardly disposed to form a handle portion, a blade-like cutter at the side of the flat guiding face of the head opposite the handle portion and disposed in a plane lower than and parallel with said guiding surface, and arms projecting upwardly from opposite ends of the cutter and slidably held in said guideways.

9. A household tool comprising a body having its under side formed with a flat

guiding surface, a handle for the body at one side of the guiding face, the body having upstanding end portions formed with straight guideways, a blade-like cutter at the side of the guiding surface opposite the handle and disposed in a plane lower than and parallel with said surface, a support for the cutter movable in the guideways, and clamping means for securing the support in any position to which the cutter may be adjusted.

In testimony whereof I affix my signature in presence of two witnesses.

THOMAS McG. AIKEN.
